UNITED STATES PATENT OFFICE.

ALFRED GILBERT, OF BIRMINGHAM, ENGLAND.

MANIFOLDING DEVICE.

1,026,308.

Specification of Letters Patent. Patented May 14, 1912.

Application filed December 30, 1910. Serial No. 600,198.

To all whom it may concern:

Be it known that I, ALFRED GILBERT, a subject of the King of England, and resident of Birmingham, England, have invented an Improved Manifolding Device, of which the following is a specification.

My invention has reference to improved means for manipulating carbon sheets in conjunction with typewriting machines and the like and consists of an improved construction of carrier sheet made of paper or other suitable material for holding a carbon sheet and the papers on which the type writing is to be made.

My said invention is constructed and adapted for use in the manner which I will describe by referring to the accompanying drawings of which:

Figure 1 is a longitudinal section of my invention; Fig. 2 is also a longitudinal section of my invention showing the carbon sheet in position ready to be held and gripped thereby; Fig. 3 is a longitudinal section of my invention with the carbon sheet in position ready to be used in the typewriting machine. Fig. 4 is a plan of my invention with the carbon sheet held thereby as in Fig. 3, parts of my invention and the carbon sheet being torn away so as to show the construction and arrangement, and Fig. 5 is a longitudinal section of a slightly modified form of my invention.

My invention consists of a base sheet A of paper or other suitable material and a binder strip B of similar material fixed thereto. The base sheet A is of rectangular shape and preferably somewhat larger than the carbon sheet C with which it is required to be used. The binder strip B is a folded or doubled strip agreeing in its length with the width of the base sheet A. A portion 1 of the folded or doubled part of the binder strip B is in its entire length glued or otherwise fastened together so that in cross section at right angles to the folded or doubled part of the binder strip B is in the shape of the letter Y, see Fig. 1 the stem 1 of the Y, representing the glued portion of the fold while the two forks 2, 3 of the Y are formed

by the two thicknesses of the binder strip 50 opening apart from the longitudinal line 4 where the gluing or sticking together of the two thicknesses terminates.

The edge 5 of the base sheet A is inserted in the binder strip between the forks, 2, 3, 55 of the Y to the outer part of one of which namely the fork 3 the base sheet is glued or otherwise fastened at 6, so that the innermost extreme edge 5 of the base sheet is for a short distance left free from the fork 3. 60

My invention is used as follows:—The binder strip B is folded completely under the base sheet A folded at the point 4 as in Fig. 1, A. The carbon paper C is inserted between the base sheet A and the fork 3. 65 The binder strip B is now turned back into position as in Fig. 3 carrying with it the carbon sheet C which thus becomes folded over the upper edge of the base sheet A as shown in Fig. 3 and is firmly held and 70 gripped between the forks 2, 3, of the forked gripping strip B. Several sheets of carbon paper may be inserted together and in the same manner. The upper fork or flap 2 of the binder strip serves as a register for inserting the various papers to be used in conjunction with the carbon sheet as the edges of these papers have to be knocked up to the line 4 from where the forks 2, 3, of the forks of the Y spring. The Y section binder strip 75 B may be either formed by folding one strip of material and gumming or otherwise sticking the two thicknesses together to form the straight limb 1 of the Y as in Figs. 1, 2, 3, and 4, or the same section strip can be 80 constructed as in Fig. 5, of two strips, one of which will form the fork 2 of the Y and one thickness of the straight limb or stem 1, and the other strip will form the other fork 85 3 of the Y and the other thickness of the stem 1. When the Y is made of two separate strips as above described and as shown in Fig. 5, the edge 8 of the one strip is by preference made to project somewhat beyond the edge 9 of the other strip so as to 90 facilitate the insertion in the typewriter of the carrier sheet with the carbon sheets and other papers.

95

Having now fully described my said invention what I claim and desire to secure by Letters Patent is:—

The herein-described manifolding device, 5 comprising the combination, with a fork-shaped binder strip (B) of paper, of an extension (6) integral with one member of the fork, and a base sheet (A) also of paper, to the underside and near the end of which the 10 said extension is glued in such a manner

that the edge of the base sheet projects between the fork members, substantially as and for the purpose specified and shown.

In testimony whereof I have hereunto set my hand in the presence of two subscribing 15 witnesses.

ALFRED GILBERT.
